UNITED STATES PATENT OFFICE.

JULIUS SCHMOHL, OF CHICAGO, ILLINOIS, ASSIGNOR TO THE BARNHART BROS. & SPINDLER, OF SAME PLACE.

DESIGN FOR A FONT OF PRINTING-TYPE.

SPECIFICATION forming part of Design No. 25,015, dated December 24, 1895.

Application filed August 26, 1895. Serial No. 560,605. Term of patent 7 years.

To all whom it may concern:

Be it known that I, JULIUS SCHMOHL, a citizen of the United States, residing at Chicago, county of Cook, and State of Illinois, have invented and produced a certain new and original Design for a Font of Printing-Type, which is fully set forth in the following specification, reference being had to the accompanying drawings, forming a part thereof.

This design comprises upper and lower case letters, character "&," dollar-mark, Arabic numerals and points. Its general characteristics are that it is a quite condensed type approximating the "Roman." It is devoid of hair-lines. Lower-case letters b, d, p, and q have their oval elements thinned almost to a hair-line at the middle part of the convex outer curve and made heavy at their junctions with the stems, respectively, the characteristic constituting what may be called a "reversed swell shade." All vertical stems have short heavy ceriphs, usually at one side only, as at the upper ends of such stems as in case of b, d, h, i, j, k, l, p, and r; also in lower-case t the stem is blended with the cross at the left side as if such a ceriph had terminated the stem and extended down to the cross. A has

the characteristic cross set exceptionally low, and the stems blend with their ceriphs at the inner side in slight curves which makes the 30 opening below the characteristic cross and between the inner surface of the stems approximate a half-moon in shape. Q has its characteristic in the form of a pear-shaped projection resting on the line. Numeral 35 character 2 has its horizontal base-line finished obliquely and with ceriphs projecting both up and down. The lower elements of numerals 3 and 5 are swelled at the upper part and reduced to their least width just 40 back of their termination, so that they terminate in elongated knobs in form resembling a pendent drop of viscid liquid.

I claim—

The design for a font of type herein shown 45 and described.

In testimony whereof I have hereunto set my hand, in the presence of two witnesses, at Chicago, Illinois, this 17th day of August, 1895.

JULIUS SCHMOHL.
